UNITED STATES PATENT OFFICE.

RICHARD C. BLAKE, OF CINCINNATI, OHIO.

HIGH OR LOW WATER ALARM.

SPECIFICATION forming part of Letters Patent No. 745,317, dated December 1, 1903.

Application filed September 29, 1902. Serial No. 125,190. (No model.)

To all whom it may concern:

Be it known that I, RICHARD C. BLAKE, a citizen of the United States of America, and a resident of Cincinnati, county of Hamilton, State of Ohio, have invented certain new and useful Improvements in High and Low Water Alarms, of which the following is a specification.

The object of my invention is to simplify the construction of alarms for indicating that the water in the boiler has reached either the high or low water limit.

In the accompanying drawings I have illustrated a water-alarm embodying my invention.

Figure 1 shows a boiler in longitudinal section with a water-column attached to the end thereof, being shown partly in section and partly in elevation to expose the float which actuates the valve of my water-alarm, which is shown secured to the column in elevation, the index-hand secured to the end of the valve-stem being shown broken off. Fig. 2 is a view of the alarm embodying my invention similar to Fig. 1, but upon an enlarged scale and showing the indicator in elevation. Fig. 3 is a top plan view of the alarm embodying my invention upon an enlarged scale. Fig. 4 is a vertical sectional view of the same, taken upon line *xx*, Fig. 3. Fig. 5 is a sectional view taken upon line *yy*, Fig. 4. Fig. 6 is a sectional view taken upon line *vv*, Fig. 4.

Referring to the parts, a column A is secured to the boiler A' so that the central point of the column comes at the true water-line of the boiler, which is indicated in Fig. 1 by a line marked O. Column A has at its lower end a pipe *a*, which puts it in communication with the water in the boiler, and at its upper end a pipe *a'*, which puts it in communication with the steam in the boiler. Secured to the column A at true water-line is a valve-casing B, which has a vertical channel *b*, which communicates through pipe *b'*, leading into the lower end of the channel, with the steam in the upper part of the boiler. Seated in channel *b* is a horizontal plug-valve C, whose stem *c* projects into column A at true water-line and has secured upon its end a rod *d*, which at its outer end receives a float D. When the float D is moved by the water rising or falling, it rotates plug C, whose lap and lead are made of a size such that when the water reaches

either high-water line, which is indicated by line 1, Fig. 1, or low-water line, which is indicated by line 2, Fig. 1, the channel *b* will be 55 opened to allow the steam to pass up to whistle E, which is seated upon the valve-casing in communication with the upper end of the channel *b*. To give the plug-valve C the proper amount of lap and lead, I prefer to 60 cut a groove *c'* in the plug-valve, which extends around the lower side of the valve upward, leaving the upper side of the valve intact upon each side of the channel for a distance equal to the number of degrees through 65 which the arm *d* travels in going either from true water-line to high or to low water line, so that when the float D is carried to either high or low water line the valve C is rotated, so that groove *c'* puts the upper end of channel *b* into communication with the lower end thereof, and thereby opens the communication between the whistle and the steam in the boiler. 70

Valve-stem *c* has an extension *c'*, which extends through the outer side of the valve-casing B and upon its outer end receives an index-hand F, the outer end of which is over a graduated plate F'. When float D is at true water-line the index-hand F points to "0" 75 upon the graduated plate F', and as the float descends or rises the index-hand does likewise, the graduations upon the plate being spaced so that the number of inches the float is away from true water-line is indicated by 80 the index-hand F upon the graduated plate. Valve-casing B has likewise a drain-cock G, seated in a channel *g*, extending from channel *b* up into chamber *b*', which surrounds valve-stem *c*. Cock G has grooves *g*' *g*'' upon 85 opposite sides, so that by turning the handle *g*''' of the cock in one direction channel *b* is put into communication with the drain-port *g*''' and by turning it in the other direction chamber *b*' is put into communication with 90 the drain-port. 95

Drain-cock G is made in the form of a plug-valve tapering and held to its seat by a coiled spring *g*'''. I have not claimed this specific form of valve herein, since the same is made the subject of a separate application. 100

With a water-alarm of my construction the valve-stem of the valve, which opens communication between the signal and the

steam in the boiler, extending, as it does, into the column at true water-line, it is seen that the valve rotates through the same angle that the float passes through in rising or falling 5 with the water in the column, and therefore the exact time when the channel *b* would be opened by the valve can be regulated to the finest degree of accuracy by changing the amount of lap and lead to the valve. The 10 simplicity of my construction over those in the art is readily appreciated when it is taken into consideration that the valve which regulates the opening of steam to the signal is connected directly to the rod of the float. 15 The indicator, which is used for informing the engineer at what point the water in the boiler is before the sounding of the signal is likewise added to my alarm with only two additional parts—namely, the indicator-hand 20 and the graduated plate. The simplicity of this construction is apparent.

What I claim is—

1. A valve-casing secured to a boiler, a steam-channel extending through the casing, 25 a rotating valve within the casing seated in the steam-channel whose valve-stem extends into the boiler, a signaling device at one end of the channel, a rod secured to the end of the valve-stem, a float secured upon the outer end 30 of the rod, and a pipe for placing the steam-channel in communication with the steam in the boiler substantially as shown and described.
2. A valve-casing secured to a boiler, a 35 steam-channel extending through the casing, a rotating valve within the casing seated in the steam-channel whose valve-stem extends into the boiler, a signaling device at one end of the channel, a rod secured to the inner end 40 of the valve-stem, a float secured upon the outer end of the rod, an extension upon the valve-stem projecting through the casing, an index-hand secured upon the end of the extension, and a pipe for placing the steam- 45 channel in communication with the steam in the boiler substantially as shown and described.
3. A column secured to a boiler and communicating with the water and the steam 50 thereof, a casing secured to the column, a steam-channel extending through the casing, a rotating valve within the casing whose valve- stem extends into the column, a signaling device at one end of the channel, a rod secured 55 to the inner end of the valve-stem, a float secured upon the outer end of the rod and a pipe for placing the steam-channel in com-

munication with the steam in the boiler substantially as shown and described.

4. The combination of a valve-casing secured to a boiler at true water-line, a steam-channel extending through the casing, a signaling device at one end of the steam-channel, a pipe leading from the steam in the boiler into the other end of the channel, a rotating valve between the signaling device and the pipe and having a stem extending into the boiler at true water-line, a rod secured to the end of the valve-stem and a float upon the rod, whereby when the water in the boiler reaches a predetermined limit the valve puts the signal in communication with the steam substantially as shown and described.

5. The combination of a water-column secured to a boiler and communicating with the water and the steam therein, a valve casing secured to the water-column at true water-line a steam-channel extending through the casing, a signaling device at one end of the steam-channel, a pipe leading from the steam 8c in the boiler into the other end of the channel, a plug-valve seated in the casing across the channel between the signaling device and the pipe and having a valve-stem extending into the casing at true water-line, a rod secured to the end of the valve-stem upon the inside of the column, and a float upon the rod whereby when the water in the boiler reaches a predetermined limit the valve puts the signaling device in communication with the steam substantially as shown and described.

6. The combination of a water-column secured to a boiler and communicating with the water and the steam therein, a valve-casing secured to the water-column at true water-line a steam-channel extending through the casing, a signaling device at one end of the channel, a pipe at the other end of the channel to place it in communication with the steam in the boiler, a rotating valve in the 95 casing seated in the channel and having a valve-stem extending into the water-column upon one side and through the valve-casing upon the other side, an arm secured upon the end of the valve-stem upon the interior of the 105 column, a float upon the rod, an index-hand upon the end of the valve-stem upon the outside of the casing, and an indicator-plate secured to the column adjacent to the indicator-hand substantially as shown and described.
